US0D1097963S

(12) **United States Design Patent** (10) **Patent No.:** **US D1,097,963 S**
(45) **Date of Patent:** **** Oct. 14, 2025**

(54) **WHEEL RIM FOR VEHICLES**

(71) Applicant: **Dr. Ing. h.c. F. Porsche**
Aktiengesellschaft, Stuttgart (DE)

(72) Inventor: **Michael Gallert**, Stuttgart (DE)

(73) Assignee: **Dr. Ing. h.c. F. Porsche**
Aktiengesellschaft (DE)

(**) Term: **15 Years**

(21) Appl. No.: **29/955,836**

(22) Filed: **Aug. 5, 2024**

(30) **Foreign Application Priority Data**

Feb. 6, 2024 (EM) 015049911-0016

(51) **LOC (15) Cl.** **12-16**

(52) **U.S. Cl.**

USPC **D12/211**
